SERVICE STRIPE HOLDER AND CLIP

Meyer P. Cohen, Columbia, S. C.

Application July 23, 1952, Serial No. 300,434

3 Claims. (Cl. 40—1.5)

The present invention relates generally to military ribbon mountings and is more particularly concerned with an improved construction thereof including novel means for fastening the same to a garment.

A principal object of the present invention is to provide a simple, rugged and unitary mounting which is adapted to receive and hold one or more military ribbons and which is adapted to be fastened to a garment by novel means.

Another object of the present invention is to provide such a mounting which consists essentially of a single holder suitably shaped, molded, extruded or otherwise formed of transparent plastic material.

Still another object of the present invention is to provide such a mounting in which the transparent holder is simple and inexpensive and not only preserves the original condition and appearance of the service ribbons, but also enhances their appearance by affording a magnified view thereof.

Other objects and advantages will become apparent to persons skilled in the art from the following specification and the accompanying drawings which serve to illustrate the invention, it being understood that variations thereof falling within the scope of the appended claims will be apparent to persons skilled in the art.

In the drawings:

Figure 1 is a perspective view of the rear of one form of the mounting as constructed in accordance with the principles of the present invention;

Figure 2 is a perspective view of the front of the mounting shown in Figure 1, the parts being shown in disassembled condition and the fastening buttons shown in Figure 1 being omitted;

Figure 3 is a rear elevation of the mounting shown in Figures 1 and 2, parts being broken away or omitted for the sake of clarity and a locking plate for the mounting being shown in broken lines;

Figure 4 is a section on line 4—4 of Figure 3 looking in the direction of the arrows;

Figure 5 is an enlarged section on line 5—5 of Figure 4 showing the mounting fastened to a garment;

Figure 6 is a view of the blank from which a retaining element of the present invention is formed;

Figure 7 is a rear view of a retaining member formed from the blank shown in Figure 6;

Figure 8 is the same as Figure 7 but shows the retaining member fitted with a pointed prong;

Figure 9 is a rear view of a modified form of the invention; and

Figure 10 is an end view of the modified form of the invention shown in Figure 9, being taken on line 10—10 of the latter view and showing the fastening button and a backing plate, the latter being shown in broken lines.

The ribbon carrier or mounting of the present invention consists essentially of a single structural unit which is adapted to receive several ribbons. Essentially, this structural unit comprises a rigid bar formed of a suitable transparent plastic material which may be manufactured in

2

any length desired and then cut to suitable unit length. While these bars may be shaped or formed by a variety of processes, the preferred manner is to extrude the material into the shape of an elongated bar having formed in the rear face thereof a single channel as shown in Figures 1 to 5, inclusive, or a plurality of channels as, for example, shown in Figures 9 and 10. These channels extend the full length of the extruded bar and are open-ended, as shown, so that one or more ribbons may be slidably inserted into or removed from each channel. On its frontal face the transparent bar of plastic is externally shaped by the same extrusion operation to provide a transversely convex surface coextensive with the plane base surface of the ribbon receiving channel whereby to form an elongated magnifying lens immediately overlying the frontal surfaces of the service ribbons mounted in the holder.

In the form of the invention illustrated in Figures 1 to 5, inclusive, the rear surface of the bar 10 is undercut to provide a single channel 11 having inwardly extending coplanar flanges 12—12, the channel 11 being adapted to slidably receive one or more service ribbons 13 when the latter are inserted endwise into the channel. The frontal surface of the channelled portion of the bar 10 is transversely curved, as at 14, to provide the channel with an effective plano-convex lens which serves to magnify the ribbons mounted in the channel and so enhances their appearance and display.

For retaining the service ribbons 13 in the channel 11 each end of the bar 10 is fitted with an element 15 which is formed from a sheet metal blank 16. Referring to Figure 6, it will be observed that the blank 16 is provided with rectangular cuts 17—17 respectively opening on opposed edges thereof and forming therebetween a constricted portion 18 which is flanked by wing portions 19 and 20, the former having a terminal edge 21 which is rounded and the latter having a terminal edge 22 which is straight. Now referring to Figure 7, it will be observed that in forming the element 15 from the blank 16, the wing portion 19 of the latter is turned so that it is disposed normal to the constricted portion 18 and the wing portion 20 and that the opposed marginal portions of the latter on opposite sides of the constricted portion 18 are offset in the same direction and are disposed in coplanar relation, forming therebetween a channel which narrows in width from the constricted portion 18 toward the terminal edge 22. Now referring particularly to Figures 2, 5 and 8, it will be observed that the retaining element 15 is provided with a pointed prong 23 which projects through an opening in the base wall of the channel formed as hereinabove described, the prong 23 being disposed proximate the terminal edge 21 and the head thereof being suitably anchored to the aforementioned base wall.

The opposed offset marginal portions of the wing 20 slidably, snugly fit between the proximate portion of the service ribbon 13 and the coplanar flanges 12—12 of the holder 10, and the prong 23 projects rearwardly from the holder 10. When the retaining element 15 is fully engaged with the holder 10, the wing portion 19 thereof abuts the end of the holder 10 and closes the end of the channel 11, thus preventing the service ribbon 13 from being dislodged from the holder. When the bar 10 is to be fastened to a garment, it is pressed against the fabric of the garment so that the prongs 23—23 of the retaining elements 15—15 at opposite ends thereof pierce the fabric as shown in Figure 5, the fabric of the garment being designated by the numeral 24. Quick-releasable safety buttons 25—25 of any conventional form are then engaged with the prongs 23—23 to secure the bar 10 to the garment 24. If desired, the display may be further enhanced by interposing between the bar 10 and the fabric

24 a plate 26 the width and length of which are greater than those of the holder 10 so that the marginal portions of the plate 26 are exposed to view and serve as a frame for setting off the holder 10 and the contents thereof. It will be understood that the plate 26 is provided with openings 27-27 through which the prongs 23-23 project freely, and it will be further understood that both the bar 10 and the plate 26 may be longitudinally bowed outwardly slightly to conform with the contour of the human chest in order for the unit to fit neatly thereagainst.

The ribbons 13 may be of any suitable material, but are preferably made of semi-rigid material so that they may be slidably inserted into or removed from the channel. Thus, the ribbons may be of cardboard with printed colors, or they may be of the customary textile, in either of which cases the ribbons are preferably rendered semi-rigid by a coating of transparent plastic material.

Figures 9 and 10 show a modification wherein the ribbon carrier or mounting comprises a transparent bar 28 having three open-ended channels 29 which extend the full length of the bar, each channel being provided with opposed inwardly extending co-planar flanges 30-30. The proximate flanges of the central channel and respectively of the outer channels are integrally joined, as shown, to provide relatively broad strips 31-31 between the several channels, which latter are each adapted to slidably receive one or more service ribbons 13 when the latter are inserted endwise into the channels. The frontal surface of each channeled portion of the bar 28 is transversely curved, as at 32, to provide each channel with an effective plano-convex lens.

For retaining the service ribbons 13 in the central channel 29 each opposite end portion of the latter is provided with a retaining element 15 as hereinbefore described in connection with the holder 10. The opposite end portions of the outer channels 29-29 are each provided with a retaining element 33, which is identical to retaining element 15 except that it does not have a prong 23. It will be understood that a backing plate designated by the numeral 34 in Figure 10 is optional.

It will be apparent that the mount of the present invention may be formed with any suitable number of closely adjoining parallel channels. Also, it may be desirable in certain instances to initially extrude the bar in the form of a multiple-channel member and then cut it lengthwise to provide either a single channel or a dual channel unit of any desired practical length. Further, a multiple channel unit may be longitudinally and transversely cut, as desired in a given unit, as where it is desired to mount three service ribbons in one channel and two service ribbons in an adjoining channel of the holder. In such case, the unit would be so cut as to center the shorter channel above the longer channel to present a balanced appearance for the cluster of ribbons inserted in the multiple-channel holder.

It will be understood, of course, that the present invention is susceptible of various changes and modifications which may be made from time to time without involving any departure from the general principles or real spirit thereof, and it is accordingly intended to claim the

same broadly, as well as specifically, as indicated in the appended claims.

What is claimed as new and useful is:

1. A military ribbon mounting comprising an elongated rigid bar undercut upon its rear face to provide a longitudinally extending channel adapted to slidably receive a military ribbon inserted endwise into the channel, said bar being formed of transparent material whereby to render said ribbon visible through the frontal face thereof, the side walls of said channel being respectively provided with opposed inwardly turned co-planar flanges which form with the base wall of the channel opposed grooves for receiving the opposite side edges of said ribbon insert, and means carried by said bar for detachably securing the same to a garment, said securing means including a pair of plate members respectively at opposite ends of said bar each having a pair of opposite end wing portions joined by an intermediate constricted portion, one of said wings being adapted to be positioned behind said ribbon insert with opposite side coplanar marginal portions thereof removably seated respectively within the grooves formed on opposite sides of the channel, said constricted portion extending from said one wing outwardly in the plane of said flanges, and the other of said wings extending forwardly from said constricted portion across the end of said bar in abutting relation thereto, and a pronged element for each plate member projecting rearwardly of said bar for engagement with a coacting removable fastener.

2. In a mounting as defined in claim 1 wherein the groove-seated opposite side marginal portions of each plate member channel-engaging wing are joined by a rearwardly offset wing portion disposed in the plane of the channel side wall flanges, and the prong element for the plate member is terminally secured to said offset wing portion.

3. In a mounting as defined in claim 1 wherein the groove-seated opposite side marginal portions of each plate member channel-engaging wing are joined by a rearwardly offset wing portion disposed in the plane of the channel side wall flanges, said offset wing portion being tapered so as to adapt the inner end portion thereof for use as a pilot to facilitate insertion of the wing into the channel.
